CLAIM

The ornamental design for a customizable shoe insole, as shown and described.

DESCRIPTION

FIG. 1 is a bottom view of the first embodiment showing a right customizable shoe insole, the bottom of the second embodiment of a left customizable shoe insole being a mirror image thereof;

FIG. 2 is a left side view of the second embodiment showing a left customizable shoe insole, the left side view of the first embodiment being a mirror image thereof; and,

FIG. 3 is a right side view of the second embodiment, the right side view of the first embodiment being a mirror image thereof.

FIG. 1 shows embodiment 1. FIGS. 2-3 show embodiment 2. The appearance of the left and right side in embodiment 1 is a mirror image of FIGS. 2 and FIG. 3, and the appearance of the bottom in embodiment 2 is a mirror image of FIG. 1.
